ORNAMENTAL PANEL

Louis Blum and William J. Horgan, Jr., both of Pittsburgh, Pa., assignors to Blumcraft of Pittsburgh, Pittsburgh, Pa., a firm consisting of Hyman Blum, Louis Blum, and Harry P. Blum

Filed Dec. 13, 1963, Ser. No. 77,778

Term of patent 14 years

(Cl. D13—7)

The drawing illustrates the ornamental panel of the design in a railing environment. The broken lines showing of a railing structure in the drawing is for illustrative purposes only. The ornamental panel is shown broken to indicate that it may be of varying length.

The sides of the vertical elements are stippled to indicate contrast.

We claim:

The ornamental design for an ornamental panel, as shown and described.
